UNITED STATES PATENT OFFICE.

GEORGE WESTINGHOUSE, JR., AND H. HERMAN WESTINGHOUSE, OF PITTSBURG, PENNSYLVANIA.

AIR-BRAKE CUT-OFF AND RELIEF VALVE.

SPECIFICATION forming part of Letters Patent No. 245,110, dated August 2, 1881.

Application filed April 21, 1881. (No model.)

To all whom it may concern:

Be it known that we, GEORGE WESTINGHOUSE, Jr., and H. HERMAN WESTINGHOUSE, of Pittsburg, county of Allegheny, State of Pennsylvania, have invented or discovered a new and useful Improvement in Air-Brake Cut-Off and Relief Valves; and we do hereby declare the following to be a full, clear, concise, and exact description thereof, reference being had to the accompanying drawings, making a part of this specification, in which—like letters indicating like parts—

Figure 1 is a longitudinal sectional view of our improved cut-off and relief valve. Fig. 2 is a like view detached of the diaphragm and its tubular piston. Fig. 3 is a transverse section in the plane of the line $x-x$, Fig. 1; and Fig. 4 is a view, in elevation, to a reduced scale, of the device of Fig. 1 in its ordinary arrangement for use between two half-couplings, both of which are connected to it, one at each end. In this figure the form of coupling shown is that which forms the subject-matter of Patent No. 236,388, though other suitable form of coupling may be substituted therefor, many such being known in the art.

The construction and operation of the automatic compressed-air brake now in general use are so well known and understood that it will be sufficient for present purposes to refer only to its general features. The compressed air is transmitted back throughout the train and charged into reservoirs, of which one is usually under each car. When the brakes are to be applied the engineer turns a cock, so as to lower the pressure in the brake-pipe. The back pressure then from each "auxiliary" or car reservoir shifts a "triple valve," so as to cut off back flow, and opens a port to the brake-cylinder. Restoration of air-pressure in the brake-pipe reverses the triple valve and opens an escape-port from the brake-cylinder to the open air. In adapting this system to very long trains, especially freight-trains, I have found, where two or three or more ordinary or average trains are united in one, giving, say, from thirty to fifty or sixty or more cars in one train, that the reduction of pressure and the restoration of pressure in the brake-pipe in the ordinary use of the apparatus is necessarily some-

what slow, chiefly on account of the great length of the train, and the fact that in ordinary braking only a slight reduction of pressure in the brake-pipe is necessary, and that while all cars ought to be fitted with air-brake apparatus it is quite sufficient for ordinary braking purposes if the brakes be applied on, say, twenty cars, more or less, at the forward end of the train. This (especially if a drive-wheel brake be used) will put the train practically under the control of the engineer, so that he can make ordinary stops with ease and facility, start again readily, and hold his train in check on ordinary down-grades. The brake-pipe on the number of cars supposed is not so long but that sufficient air can be readily and quickly exhausted from and again pumped or charged into the pipe to actuate and release the brakes with such celerity and power as are essential in freight-train service. At the same time, in case of emergency, or where excessive brake-power is required, the engineer ought to be able to set every brake throughout the train with maximum quickness and power.

Our present invention relates to a means for securing these desirable ends.

At any desired point in the train—say fifteen or twenty cars from the forward end—we insert in the air-conduit pipe or connection a cut-off valvular appliance of such construction that it will permit of the flow of air under pressure in one direction back through the brake-pipes so as to charge and keep charged the auxiliary reservoirs on all the cars of the train, but as against no more than the usual or a moderate reduction of the air-pressure forward, such as will shift the triple valves on the supposed fifteen or twenty forward cars, and apply the brakes of those cars, such device or appliance will close the air-conduit pipe and prevent the escape of air or the reduction of the pressure from the brake-pipe in the rear of it, and hence will practically cut off in the case supposed the braking-power of the cars in its rear, while leaving the braking-power of the cars forward free to act with the desired promptness and power. At the same time the appliance in question is so constructed that when, in case of emergency or necessity, the engineer opens full the air-pressure reducing or escape port,

or opens it more than is common or desirable in ordinary braking, an escape-port will be opened in the appliance referred to by the back-pressure, so as to permit of the escape of air from the brake-pipe of cars in the rear, whereby the triple valve on every car will be at once shifted and the brakes applied on every car with maximum force and quickness, if desired, or with relatively less force and quickness if the reduction be less.

The appliance or device referred to has a case, A A', made in two parts bolted together, and which clamp between their meeting surfaces the outer edge of a flexible diaphragm, 15 a, made preferably of india-rubber. This diaphragm is open at the center, as shown, and rests or laps onto the end of a hollow piston, a', to the radial flange of which it is secured by a clamping-ring, a², and screws a³. The 20 tubular sides of the piston a' have holes or ports s, in any desired number.

Passing lengthwise through the opening or bore of the hollow piston is a valve-stem, v, which carries a valve, v', which seats like a 25 flat-faced poppet-valve on the inner edge of the diaphragm a, and a cylindrical head, d, on the end of the stem closes and keeps closed the otherwise open end of the hollow piston. The hollow piston has, however, a short range 30 of possible motion away from the valve v' and into the annular recess d' made around the base of the cylindrical head d, and in this recess one end of a spring, e, is inserted, the other end of which bears with a moderate 35 pressure against the adjacent or under face of the piston-flange, so as to hold the valve-seat of the valve v' up against said valve. From the plane of the seating-face of the valve v' guiding-wings v² extend down to the head d. 40 The valve v' is clamped down against the ends of these wings by a screw-nut, v³, and the end of the valve-stem is guided by being passed through an eye in a spider-frame, n.

Between the spider-frame and the top or 45 back of the valve v', I arrange a spring, c', the resiliency of which is intended to be equal to or a little in excess of the amount of the reduction of air-pressure intended to be effected in the brake-pipe at the forward end of the train 50 in doing ordinary or average braking. For example, if such reduction of air-pressure is to equal or not exceed, say, fifteen pounds per square inch, then the spring c' should exert a force approximately equal to or greater than 55 fifteen pounds multiplied by the number of square inches in the diaphragm a and its movable attachments, against which air-pressure acts effectively to compress the spring c'.

The head d has a hole bored in its end in 60 the axial line thereof, in which we insert and loosely secure by a pin, e², the stem e' of a poppet-valve, e. This valve seats (when seated) on a bush, e³, which latter is slipped tightly in a seat or socket made in a bridge-piece, 65 B, which latter extends across the hollow of the half-case A', but so as to leave ports b past the outside of the bridge-piece, and also make

ports b' from the tubular openings of the bush e³ to the external atmosphere. A winged stem on the under side of the valve e plays in the bore of the bush e³, the better to guide the valve. In each end of the case thus made we screw a half-coupling, H, Fig. 4, which may be of any suitable construction; but, as shown, we prefer to use the well-known Westinghouse 75 clutch-coupling. The appliance or device thus constructed is to be arranged between and connected with the two half-couplings, which otherwise would connect the brake-pipes of any two cars, and at such point in the length 80 of the train as will give forward thereof a brake-power sufficient for ordinary purposes, but not too long for ready application; but the place in the train where it is inserted or inter-coupled is not material, and is to be left to 85 the choice or judgment of the trainman or employé to whom the matter may be intrusted.

In a train of, say, from thirty to fifty cars, more or less, the device may be arranged about midway of the train, and on longer trains a 90 convenient or advantageous point for inserting it would be anywhere along from fifteen to twenty-five cars from the forward end of the train. The train and pipes being coupled up, the engineer turns on air-pressure to charge 95 the brake-reservoirs. The operation forward of this device will be as is usual in the automatic brake. At the device, air-pressure, entering at the forward end, P, (which end must always be forward or toward the charging end 100 of the train,) will act on that side of the diaphragm a so as to compress the spring e, slide the piston a' down on the wings v² of the stem v and on the cylinder or plug d, and leave an open annular port beneath the valve v', so that 105 the air-pressure may be transmitted or pass onward through the ports s and charge the reservoirs on cars in the rear.

When the engineer wishes to apply the 110 brakes in ordinary braking he lowers the air-pressure in the usual way, so as to operate the brakes in the usual way forward of the device thus intercoupled. Ordinarily this can be done so as to apply the brakes with sufficient power 115 for ordinary purposes by a reduction of air-pressure of not to exceed ten or fifteen pounds per square inch, more or less.

As the spring c' is adjusted, as above explained, to resist a back or compressive force corresponding in amount to such reduction, 120 such back-pressure, acting on the right-hand side of diaphragm a, will perform no effect except to force the inner edge of the diaphragm over against the under or seating face of the valve v', and thereby close the charging-port. 125 The inner part of the rubber diaphragm furnishes a seat to the valve, so as to make a tight joint. The devices will then be in the relative position shown in Fig. 1, and the valve e, which governs the escape-ports b', will be seated, the 130 effective back-pressure not being sufficient to unseat it; but when in case of emergency or danger, or when for any reason more than the usual or a moderate braking-power is desired,

the engineer opens his cock, so as to lower the pressure in the brake-pipe to an amount more than the supposed ten or fifteen pounds commonly not exceeded in ordinary braking. As a consequence of this, the pressure on the left of the diaphragm a being so much reduced, the back air-pressure on the right of said diaphragm will then become effective in compressing the spring c' , and consequently the diaphragm a , with its hollow piston a' , valve v' , and head d , carrying the valve e , will be shifted to the left a greater or less distance, according to the amount of the supposed reduction, and the unseating of the valve e opens the escape from the rear brake through the ports b' . The pressure being thus reduced in the rear brake-pipe, the back-pressure of the air in the auxiliary reservoirs connected therewith will shift the corresponding triple valves and the brakes will be applied throughout the train.

If the train has, say, from sixty to eighty cars, two or more such cut-off appliances may be employed at proper intervals along the train, the spring c' being so set in each case that any reduction of air-pressure forward in excess of a predetermined amount shall result in the compression of the spring and the unseating of the valve e .

Various modifications may be made in the appliance described, such as may be suggested by or copied from various triple-valve patents heretofore granted to George Westinghouse, Jr., and in fact the device in question has many of the features of construction and operation of a triple valve, the principal distinctive features being in the addition of the spring c' and in the arrangement of the charging and exit ports $P P'$ in line with each other on opposite sides of the diaphragm, instead of at right angles, as has heretofore been usual in triple valves, as an auxiliary reservoir attachment; and it may also be modified so as to embrace the valvular structure shown and described in United States Patent to George Westinghouse, Jr., No. 217,838, of July 22, 1879, or other suitable known forms of relief-valve, so called, such as may at pleasure be insertible and removable from a line of brake-pipe at a point intermediate between its ends, and such as will automatically, under the action of fluid-pressure, perform the functions set forth substantially in the manner described.

We are aware that relief-valves, so called, adapted to open an air-escape port at each brake-cylinder on the release of air-pressure in a compressed-air-brake mechanism, as distinguished from an automatic-brake mechanism, is not new; but we are not aware of any prior construction of valvular apparatus in which both the cut-off and relief or escape functions are unitedly employed, so that at one degree of reduction of pressure the cut-off function will be brought into play, and at another degree of reduction of pressure an escape-port will be opened to the external air. And it is also true that other forms or construction of couplings, such as may be used in the brake

apparatus with which the valve in question is to be used, may be attached at or connected with the ports $P P'$, instead of those shown, without any substantial departure from the scope of the present invention; or, instead of using a brake-coupling proper, other suitable form of readily attachable and detachable coupling may be employed. It should be stated, however, that the cylindrical head d performs no function of importance, and that that device is so made simply as a matter of convenience. The wings v^2 might be extended entirely down the stem, with radial ribs by which to furnish bearings for the end of the spring c , and bearings so made are included herein as the equivalents of the annular recess d' ; also, in such case the open end of the piston would be the equivalent of the ports s .

We claim herein as our invention—

1. An air-brake cut-off and relief valve adapted to be at pleasure inserted in and removed from a line of train-brake pipe at any desired point between its ends, and automatically operative under the action of the fluid-pressure in the charging of the reservoirs in cutting off the escape-port at one degree of back-pressure and opening it at another degree of back-pressure, substantially as set forth.

2. An air-brake cut-off and relief valve automatically operative under the action of the fluid-pressure, substantially in the manner set forth, in combination with a brake-pipe coupling secured to or connected with each end thereof, whereby to be readily connected with and disconnected from the ordinary brake-pipe couplings (of corresponding kind) as employed on the cars of the train.

3. In an air-brake cut-off and relief valve of the class described, the arrangement of the ports $P P'$ or coupling ends substantially in line with each other.

4. The valve-case $A A'$, having ported bridge B and valve-seat thereon, in combination with a valve, e , spring c' , and suitable interposed mechanism whereby the valve will be held to its seat as against a moderate reduction of fluid-pressure, but will be lifted from its seat and open an escape-port in case of a greater reduction of air-pressure in the brake-pipes, substantially as and for the purposes set forth.

5. In a valve-case, $A A'$, a ported bridge, B , having a valve-seat and a valve, e , thereon, in combination with spring c' , stem v , having a valve, v' , and end bearings for the spring c , diaphragm a , and hollow ported piston a' , substantially as and for the purposes set forth.

6. In a valve-case, $A A'$, a diaphragm, a , and hollow ported piston a' , in combination, by spring c , with valve v' and annular recess d' , as a means for actuating the valve of an escape-port, substantially as set forth.

7. The method of actuating brakes in long trains by interposing at one or more suitable points in the length of the brake-pipe thereof a corresponding number of automatically-acting cut-off and relief valves, substantially as set forth, and adapted to cut off or out of ac-

tion the rear section or sections of brake apparatus, as against a moderate reduction of air-pressure in the section forward, and also adapted, on a greater reduction of pressure forward,
5 to open a relief-valve on the brake-pipe of the rear section, and thereby bring the brake apparatus of the rear section into operation.

In testimony whereof we have hereunto set our hands.
